US00D921594S

(12) **United States Design Patent** (10) **Patent No.:** **US D921,594 S**
(45) **Date of Patent:** **** Jun. 8, 2021**

(54) **F-SERIES CIRCULAR CONNECTOR**

- (71) Applicant: **Hongchuan Wang**, Shenzhen (CN)
(72) Inventor: **Hongchuan Wang**, Shenzhen (CN)
(73) Assignee: **SHENZHEN CHUANTE ELECTRONIC TECHNOLOGY CO., LTD.**, Shenzhen (CN)
- (**) Term: **15 Years**
(21) Appl. No.: **29/677,392**
(22) Filed: **Jan. 19, 2019**
(51) LOC (13) Cl. **13-03**
(52) U.S. Cl. **USPC D13/154**
(58) **Field of Classification Search**
USPC D13/120, 133, 146, 148, 149, 150, 151, D13/153, 154, 155, 157, 173, 199; D23/259, 262
CPC H01R 4/00; H01R 12/70; H01R 13/052
See application file for complete search history.

(57) **CLAIM**

The ornamental design for an F-series circular connector, as shown and described.

DESCRIPTION

FIG. 1 is a top perspective view of a F-series circular connector, showing my new design;

FIG. 2 is a top plan view of the F-series circular connector of FIG. 1, shown enlarged for clarity of disclosure;

FIG. 3 is a rear elevation view of the F-series circular connector of FIG. 1;

FIG. 4 is a bottom plan view of the F-series circular connector of FIG. 1, shown enlarged for clarity of disclosure;

FIG. 5 is a right side elevation of view the F-series circular connector of FIG. 1;

FIG. 6 is a front elevation view thereof; and,

FIG. 7 is a left side elevation view thereof.

The equal-length broken lines in the drawings depict portions of the F-series circular connector that form no part of the claimed design.

1 Claim, 7 Drawing Sheets
